DESIGN FOR A PITCHER

Robert J. Kemper, San Carlos, Calif.

Application November 12, 1946, Serial No. 134,724

Term of patent 14 years

(Cl. D44—21)

To all whom it may concern:

Be it known that I, Robert J. Kemper, a citizen of the United States, residing in San Carlos, county of San Mateo, State of California, have invented a new, original, and ornamental Design for a Pitcher, of which the following is a specification, reference being had to the accompanying drawing, forming part thereof.

Fig. 1 is a top plan view of a pitcher showing my new design; Fig. 2 is a front elevation; and Fig. 3 is a side elevation thereof.

I claim:

The ornamental design for a pitcher, as shown.

ROBERT J. KEMPER.
